UNITED STATES PATENT OFFICE.

MARVIN H. JESTER, OF DENVER, COLORADO, ASSIGNOR TO THE M. H. JESTER INVESTMENT COMPANY, A CORPORATION OF COLORADO.

SUPPORTING DEVICE FOR PLASTER-BOARDS USED IN PARTITION CONSTRUCTION.

1,124,909.

Specification of Letters Patent. Patented Jan. 12, 1915.

Application filed July 29, 1912. Serial No. 712,008.

To all whom it may concern:

Be it known that I, MARVIN H. JESTER, a citizen of the United States of America, residing in the city and county of Denver 5 and State of Colorado, have invented a new and useful Supporting Device for Plaster-Boards Used in Partition Construction, of which the following is a specification.

My invention relates to improvements in 10 supporting devices for plaster boards used in partition and ceiling construction.

The object of the invention is to provide either a vertical or horizontal support in the form of a channel bar, the ends of which are 15 adapted to be secured to the floor and ceiling respectively, a plurality of said bars being used and spaced to correspond to the length of the plaster boards, U-shaped clips being placed upon the bars, having lateral wings 20 which form backings for the ends of the plaster boards, nails being driven through apertures in the bars and through registering horizontal slots in the clips, so as to bear against the outer faces of the adjoining ends 25 of two boards, whereby the ends of the said boards are securely clamped between the nails and the wings of the clips, their adjoining ends abutting against the sides of the clip.

These objects are accomplished by the device illustrated in the accompanying drawings, in which:

Figure 1, is a front elevation of a partition, showing plaster boards secured and 35 supported by my improved device. Fig. 2, is an enlarged horizontal sectional view on the line 2—2 of Fig. 1. Fig. 3, is a perspective view—full size—showing a portion of one of the upright bars, with a clamping device 40 thereon, comprising a clip, and a nail, which pass through the bar and clip. Fig. 4, is a side view of the arrangement illustrated in Fig. 3. And Fig. 5, is a side view of a modified form of clip.

Similar letters of reference refer to similar parts throughout the several views.

Referring to the accompanying drawings—The numeral 1 designates the upright supports, which are preferably in the form 50 of metal channel bars, and are secured at their ends to the floor and ceiling, the channel bar form of upright possessing the necessary strength and rigidity for the purpose required. These uprights are spaced at intervals corresponding to the length of the

plaster boards employed, which are usually thirty-six inches long by about thirty inches wide, with a thickness of about three-eighths of an inch. These boards 2, are laid one above the other, between the uprights, as shown in Fig. 1, their ends abutting against the said uprights, and they are secured thereto in the following manner. The web of each upright is provided with a plurality of holes 3, which may be equi-distant, and so disposed with respect to the width of the boards that two holes occur at points between the end corners of each board, as shown, the uprights being positioned with their side members facing toward the front 70 and rear respectively. Upon the uprights, at points coincident with the holes 3, are placed clips 4, comprising U-shaped members 5, the sides of which terminate in lateral wings 6, which lie at right angles to the 75 said sides. The depth of the U-shaped members of the clips is equal to the width of the channel bar uprights, so that when the clips are placed upon the uprights their wings will lie substantially flush with the adjacent 80 side of the uprights, as clearly shown in the drawings. The U-shaped portions of the clip are adapted to fit snugly upon the upright, and by bending the sides of these U-shaped portions slightly toward each other, 85 or so that they converge, it will be necessary to spring the clips in placing them on the uprights, and they will thus be held in position upon the uprights by the resilient clamping engagement of their side members 90 with the said uprights.

The U-shaped member 5 of each clip is divided by a transverse slot 7, which extends through its closed end and into its parallel sides to points adjacent to the wings 95 6, and when the clips are in position on the uprights, the slots 7 register with the holes 3, in the uprights, as will appear by reference to Fig. 4.

In connection with the clips, I employ 100 wedges 8, preferably wire nails of the required size, which are driven through the holes 3 in the uprights, and through the slots 7 in the bodies of the clip in such manner as to clamp the adjoining ends of two 105 boards between the said nail and the wings of the clip, and this is accomplished in the following manner: The boards being approximately three-eighths of an inch thick, the holes 3 in the web of the uprights, 110

which are of slightly greater diameter than the diameter of the nails, are so positioned relatively to the widths of the said webs that where a nail is inserted in one of the holes 3, 5 it will contact with the outer margin of the said hole, and with the adjoining ends of the boards, and the head of the nail being of greater diameter than its shank portion, its engagement with the plaster board will 10 cause its shank to pass through the hole 3, at a slight angle to the axis of the said hole, thus converting the nail into a wedge, between which and the wings of the clips the ends of the boards are securely clamped. 15 The holes 3 may be placed any suitable distance from either side of the center of the bar, so as to allow for varying thicknesses of plaster boards.

In operation, the clips are first sprung 20 upon the uprights, with their slots registering with the holes in the said uprights, and the plaster boards are placed between the pairs of uprights, with their adjoining end portions resting against the wings of the 25 said clips, as shown in Fig. 2, the boards being placed one upon the other until they reach from floor to ceiling, the nails are driven through the uprights and through the slots in the clips, as each board is placed 30 in position, and thus clamp the adjoining ends of the boards in the manner above described. After the boards have been secured to the uprights, they are covered on

their opposite sides with a coating of plaster or cement, after which the usual finishing or smooth coating is applied, which completes the partition.

In Fig. 5, I have illustrated a modified form of clip 9, in which the sides of the U-shaped portion are provided with elongated 35 holes 10, which take the place of the slots 7. In other respects, this clip is the same as that shown in the other views.

Having described my invention, what I claim as new and desire to secure by Letters Patent, is:

A supporting device for plaster-boards comprising an apertured channel-bar, a narrow U-shaped clip sprung over said channel-bar having in each leg an elongated slot 50 parallel with the upper edge of said clip and registering with an aperture of said channel-bar, wing-plates on said clips adapted to lie behind the plaster-boards, and a wedge-member extending through said 55 apertures and slots adapted to engage and press inwardly on the plaster-boards along its end portions only and to exert an outward pressure on said channel-bar at its center.

In testimony whereof I affix my signature in presence of two witnesses.

MARVIN H. JESTER.
